UNITED STATES PATENT OFFICE

GEORGE J. MEYER, OF MILWAUKEE, WISCONSIN, ASSIGNOR TO GEO. J. MEYER MANUFACTURING COMPANY, OF CUDAHY, WISCONSIN, A CORPORATION OF WISCONSIN

BOTTLE CAPPING MACHINE

Application filed November 10, 1930. Serial No. 494,657.

The invention relates to container closing machines and more particularly to machines for capping bottles.

An object of the invention is to provide a bottle capping machine including a revolvable group of capping or crowning devices which are successively operated by reciprocating actuating means common to the group.

Another object of the invention is to provide a bottle capping machine in which the capping devices are provided with flat-topped segments engageable by the reciprocating actuating means, and in which the successive capping devices are both depressed and elevated by the actuating means.

A further object of the invention is to provide a capping machine including capping heads, the lower portions of which are swingably mounted for facilitating the removal of defective crowns.

A further object of the invention is to provide a bottle capping machine in which the capping heads are equipped with yieldingly mounted ledges onto which the crowns are deposited preceding the crowning operation.

A further object of the invention is to provide a bottle capping machine including a simple but effective crown selector for properly entering the crowns into the crown chute.

A further object of the invention is to provide a bottle capping machine in which the crown hopper is provided with an interior perforated bottom for facilitating removal of foreign matter from the crowns, and in which the crown selector is pivotally mounted on the crown hopper for expediting access to the interior of the hopper and selector.

A further object of the invention is to provide a bottle capping machine including a crown chute which is so constructed as to facilitate the movement of crowns therewith, and which has its lower end equipped with a movable gate for facilitating the removal of defective crowns.

The invention further consists in the several features hereinafter set forth and more particularly defined by the annexed claims.

This application constitutes a continuation in part of my co-pending application for

Filling and capping machine, Serial No. 189,548, filed May 7, 1927.

In the accompanying drawings, Fig. 1 is a side elevation of a bottle capping machine embodying the invention;

Fig. 2 is a sectional view of the machine taken along the line 2—2 of Fig. 1;

Fig. 3 is a longitudinal section taken along the line 3—3 of Fig. 1;

Fig. 4 is a sectional elevation of the lower portion of the machine;

Fig. 5 is a sectional view taken along the line 5—5 of Fig. 4;

Fig. 6 is a detail sectional view taken along the line 6—6 of Fig. 3;

Fig. 7 is a detail sectional view taken along the line 7—7 of Fig. 3;

Fig. 8 is a detail view partly in section showing the capping head depressing means as it appears near the beginning of the capping operation;

Fig. 9 is a similar view showing the capping head depressing means near the end of the capping operation;

Fig. 10 is a detail sectional view taken along the line 10—10 of Fig. 6;

Fig. 11 is a detail view showing the upper ends of a number of adjacent capping heads;

Fig. 12 is a detail sectional elevation of the lower portions of one of the capping heads;

Fig. 13 is another sectional elevation of the lower portions of one of the capping heads taken at right angles to the plane of Fig. 12;

Fig. 14 is a detail elevation of the lower portions of the capping head;

Fig. 15 is a bottom view of two adjacent capping heads as they appear when assembled on the machine;

Fig. 16 is a detail sectional view showing one of the crowning supporting ledges of Fig. 12 in its retracted position;

Fig. 17 is a detail elevation of the upper portion of the capping machine, a crown chute and crown selector thereof being shown in vertical section;

Fig. 18 is a detail sectional view of a crown rejector;

Fig. 19 is a detail view of the lower end portion of the crown chute;

Fig. 20 is a transverse sectional view of the

crown chute taken along the line 20—20 of Fig. 17;

Fig. 21 is a similar view taken along the line 21—21 of Fig. 17;

Fig. 22 is a front elevation of the crown selector, parts being broken away and parts being shown in section;

Fig. 23 is a fragmentary top plan view of the crown hopper, the crown selector 10 thereof being shown in open position;

Fig. 24 is a detail view showing the inner face of the crown selector;

Fig. 25 is a fragmentary sectional view of the discharge portion of the crown selector 15 showing an improperly presented crown;

Fig. 26 is a similar view showing a properly selected crown;

Fig. 27 is a vertical sectional view of a modified form of capping machine;

Fig. 28 is a vertical sectional view taken along the line 28—28 of Fig. 27;

Fig. 29 is a sectional view taken along the line 29—29 of Fig. 27, and

Fig. 30 is a sectional view taken along the line 30—30 of Fig. 29.

In that embodiment of the invention shown in Figs. 1 to 26 inclusive, the numeral 35 designates a hollow base which in practice may form a part of a combined filling and closing machine. A bearing bracket 36 includes a flat upper portion secured to the upper wall of the base, as by screws 37, and includes a cup-shaped portion 38 depending into the interior of the base. An upright tubular standard 39 has its lower reduced end portion secured in the reduced lower end of the bearing bracket 36, as by means of a bolt 40. A sleeve 41 is journaled about the tubular standard 39 and has its lower end portion extending into the cup-shaped portion 38 of the bearing bracket 36, where it is provided with a driving gear 42. A cover 43 receives the rotary sleeve 41 therethrough and is secured to the bearing bracket to close the space in which the gear is housed.

A bearing frame 44 is disposed within the hollow base 35 and is fixedly secured to the depending portion of the bearing bracket 36 to and also to the lower portions of the base. A horizontally extending shaft 45 is journaled in the frame 44 and is driven by any suitable source of power. A pair of spaced pinions 46 are secured to the shaft 45 and mesh with gear wheels 47 secured to the opposite end portions of a horizontally extending shaft 48 which is journaled on the frame 44 in parallel relation to the shaft 45. A bevel pinion 49 is secured to the shaft 48 and meshes with a superposed bevel gear 50 which is secured to a gear 51, the latter gear being journaled on an upright stationary shaft 52 secured in the bearing frame 44 and in the bearing bracket 36. The gear 51 meshes with the gear 42 for rotating the sleeve 41 and also

meshes with a large diameter gear 53 which forms part of a bottle filling mechanism, not shown.

The gear wheels 47 carry aligned crank pins 54 at their outer faces. These crank pins are journaled in blocks 55 slidably mounted in channels 56 formed in the spaced arms of a U-shaped rocker frame 57, which is pivotally supported on a bracket 58 secured to the lower portions of the base 35. A trunnion 59 is journaled in the rocker frame 57 to swing about a horizontal axis, and is provided with a depending boss 60 which is internally threaded to receive the threaded lower end of a reciprocating rod 61 housed within the tubular standard 39. The oscillation of the rocker frame by its crank connection with the gears 47 acts to reciprocate the rod 61 simultaneously with the rotation of the sleeve 41. By this construction, the loads on the bearings are reduced and equalized and a heavy load can be imposed on the rod 61 without causing racking of the rocker frame or the driving connections.

A circular table 62 is carried on an intermediate portion of the sleeve 41 and is provided at its upper surface with resilient bottle-supporting pads 63. A star wheel 64 is secured above the table and, in the present instance, is provided with five bottle-receiving notches. The upper end portion of the tubular standard 39 is internally threaded to receive therein the lower end portion of an exteriorly threaded sleeve 65. The reciprocating rod 61 passes through the sleeve 65 and is splined thereto by a key 66. An annular outstanding flange 67 is formed about the sleeve 65 and carries thereon the inwardly flanged portions of a capping head support 68 which latter includes a depending tubular portion 69, the lower end of which fits about the tubular standard 39 and is splined thereto by a key 70. The tubular portion of the capping head support is provided with a number of annular grooves 71 to receive the inwardly extending ribs 72 of a split bushing 73. A tubular spool-shaped capping head guide 74 has its upper portion surrounding the split bushing 73 and secured thereto by screws 75, thus suspending the guide from the capping head support. The lower portions of the capping head guide slidably fit about the upper portions of the sleeve 41 to which they are splined by a key 76. The capping head guide is thus driven from the sleeve 41 and is suspended from the split bushing 73 which rotatably fits on the grooved lower end of the capping head support 68.

A bevel gear 77 is fixedly secured to the upper end of the sleeve 67 and meshes with a bevel pinion 78 carried on a horizontal shaft 79 journaled in an extension 80 formed integrally with the capping head support. At its outer end the shaft 79 carries a hand crank 81 which, when turned, serves to adjust the

mechanism for use with bottles of different height. When the crank is turned in one direction, the sleeve 67 is screwed downwardly into the standard 39, and simultaneously the 5 reciprocating rod 61 is screwed downwardly into the trunnion 59, thus preserving the proper relation of these parts.

The capping head guide 74 is provided with a pair of spaced outstanding flanges 82 10 which have a plurality of aligned openings 83 formed therein to slidably receive vertically extending capping head bodies 84. The upper ends of these bodies are provided with flat-topped arcuate segments 85, which 15 are arranged in adjacent relation in the manner indicated in Fig. 11. The outer projecting edges of the segments 85 are adapted to slidably rest on an inturned flange or ledge 86 formed on the capping head support 68, 20 as best seen in Fig. 10, and the reduced inner edge portions of each segment are adapted to slidably rest on an outstanding rib or ledge 87 formed on a sleeve 88 which fits about the outer periphery of the capping 25 head guide 74 and is secured to the capping head support by one or more screws 89. The inner edges of the segments are concave to fit about the circular periphery of the sleeve 88 and thus prevent rotation of the 30 capping heads on their axes. During assembly, the capping heads are dropped into position onto the supporting ledges 86 and 87 through an opening 90 formed in the upper portion of the head support, as seen in Fig. 35 6. As seen in Fig. 7, the tracks or ledges 86 and 87 do not extend completely around the support 68, but are spaced to form an opening somewhat longer than each segment 85, so that the capping heads may be successively 40 depressed at the capping position, as hereinafter described.

The upper end portion of the reciprocating rod 61 projects above the bevel gear 77 and carries thereon a spring housing 91. 45 The upper end of the rod is provided with a flange 92 engaging the spring housing, and a strap 93 passes over the upper end of the flange and is secured by bolts 94 to the spring housing for retaining the housing against 50 relative longitudinal movement with respect to the rod while permitting the rotary adjustment of the rod. The spring housing carries a lateral extension 95 which slidably fits about a rod 96 upstanding from the capping head support 68, thus preventing rotation of the spring housing with respect to the capping head support.

The spring housing includes upper and 55 lower flanges 97 and 98 between which is interposed a coiled spring 99 engageable with end plates 100, the upper of which is engageable with the upper flange 97 and the lower of which is engageable with the upper part of a hook-shaped member 101. The 60 spring 99 is held in compressed relation by

the end plates 100 which are adjustably connected by screws 102 entering one of the end plates, and having their head portions seated in tubes 103 secured to the other end plate. The compression of the spring is preferably 70 on the order of 800 or 900 pounds. The upper end of the spring is held in position by a plug 104 threaded into the flange 97 and passing through the upper end plate 100, and the lower end of the spring is held in position by the reduced end of a plunger 105 which is slidably mounted in a bore 106 formed in the capping head support 68, the upper portions of the plunger 105 passing through the flange 98 are non-circular to prevent rotation of the plunger. A plate 102' is disposed below the flange 98 and receives the plunger 105 therethrough. The 75 end portions of the plate are secured to screws 103' which slidably pass through the flange 98 and are secured to the lower spring plate 100 and the upper portions of the hook-shaped member 101. The lower portions of the plunger 105 are provided with a 80 downwardly diverging V-shaped opening 107 terminating at its upper end in a horizontal bore 108. A toggle member 109 has a cylindrical upper end journaled in the bore 108 and has its lower end engageable with the successively presented segments 85 of the capping heads. The toggle member 85 is normally held in the position of Fig. 8 by a spring 110, or other suitable expedient, so that during the capping operation, as hereinafter described, the toggle member will 90 pass over center as the segment moves laterally of the toggle member. The toggle member is held in position by a detachable plate 111 secured in place by a screw 112.

Each tubular capping head body 84 is exteriorly threaded at its lower end for the reception of a cup-shaped cap 113, as seen in Figs. 12 and 13. An ejector plunger 114 is housed within the capping head body and is provided with a flange 115 near its lower end portion engageable with the inturned bottom flange of the cap 113. A coiled spring 116 surrounding the ejector plunger 114 is housed within the tubular capping head body 84 and at its upper end bears against the lowermost of a number of plates or shims 117 by which the travel of the ejector plunger is adjustably limited. The compression of the spring 116 is somewhat less than the compression of the spring 99. A sector body 118 includes a tubular upper portion 119 which fits about the cap 113 and is clamped there-to by a bolt 120 passing through a vertically split portion of the sector body and entering an annular groove 121 formed in the cap. The tubular portion of the sector body also houses and retains a crowning throat or die 122 which abuts against the lower face of the cap 113 and is provided with a downwardly diverging conical crowning opening 125 130

123. A crowning tip 124 secured to the lower end of the ejector plunger 114 is disposed within the opening 123 and is provided with a concave lower face 125 engageable with the bottle crown. The sector body 118 is provided with spaced depending portions 126 between which fits a bottle centering guide 127 pivotally secured at its lower rear portions to the depending portion 126 of the sector body 10 by means of pins 128, the bottle centering guide being swingable downwardly as indicated by dotted lines in Fig. 13. Immediately below the crowning throat or die 122, the sector body 118 and the upper portion of the bottle centering guide 127 are open at forward portions for the admission of a bottle crown 129 into the space immediately below the opening 123 in the crowning throat. The bottle centering guide 127 is held in its normal position by a lever 130 pivotally mounted on a lug 131 formed on the sector body, and at its free end portion engages another lug 131' formed on the sector body, the flat upper face of the lever engaging the lower 25 face of a projecting portion 132 of the bottle centering guide, as seen in Figs. 13 and 14. At its lower portions, the bottle centering guide 127 is provided with a downwardly flaring opening 133 by which the neck of a bottle 134 is centered with respect to the crowning throat or die. The crown 129 is supported in its delivered position by resting at opposite edges on ledge members 135 pivotally suspended in opposite recessed side 30 portions of the bottle centering guide 127, as seen in Fig. 12. The pivotally suspended ledge members 135 are normally held by their weight in position to support a crown thereon preparatory to the crowning operation, but are capable of swinging outwardly as indicated in Fig. 16 to avoid interference with the crowning operation or the ejection of the crowned bottle. By the use of the swinging ledges, the crown is given a substantial support without danger of the bottle being suspended from the ledges at the time of ejection.

50 The extension 80 of the capping head support has secured thereto as by bolts 136 a superposed crown hopper 137. The crown hopper is provided with an inclined bottom 138 and an inclined perforated bottom 138' spaced thereabove, as seen in Fig. 17, to permit foreign matter to sift through and 55 to enter a receptacle 139 formed at the lower end of the hopper, the receptacle being closed by a slidably mounted door 140. A flat vertically extending wall 141 of the hopper is provided with a circular outwardly flaring opening 142 through which crowns are discharged from the hopper. An outstanding circular rib 143 is integrally formed on the wall 141 concentric with the opening 142 to rotatably receive therein a pair of 60 disk-like crown selector plates 144 and 145,

which are spaced at their outer portions. The plate 145 is provided with a hub 146 about which the plate 144 is secured as by screws 147. The hub 146 is journalled on an inwardly-projecting shaft 148 fixedly secured to the hub portion 149 of a spider frame 150, the inner ends of the hub 146 and shaft 148 being conically formed, as seen in Fig. 17, to facilitate free movement of the crowns. The spider frame 150 is pivotally mounted on pins 151 and 152 fixedly secured to lugs 153 and 154, respectively, formed on the crown hopper, thus permitting the crown selector plates to be swung outwardly from the hopper, as indicated in Fig. 23, for access to the crown selector and the interior of the hopper. The spider frame 150 is normally held in closed position by a suitable latch member 155.

70 The crown selector plate 145 has ratchet teeth 156 formed about its periphery for engagement with a spring-pressed pawl 157 carried at the outer end of a rocker arm 158 journalled on the hub portion 149 of the spider frame 150. The rocker arm is reciprocated by a vertically extending rod 159 passing substantially axially through the pivot pin 152 and secured at its lower end to an extension arm 160 fixedly carried on the spring-housing 91. The reciprocation of the spring-housing 91 by the rod 61 thus serves to rotate the selector assembly through the ratchet connection 156, 157. The crown selector plate 144 is provided with a plurality of outwardly flaring openings 161 which register with the circular opening 142 in the hopper and are separated by outstanding ribs 162 of triangular cross-section projecting through the opening 142 to form agitators. At its peripheral portions, the selector plate 144 is offset outwardly and is spaced from the similarly offset portions of the selector plate 145 to form an angular crown-receiving passage between them. A narrow shoulder 163 is formed on the offset portions of the selector plate 144 and is engageable with the flaring corrugated edge portions of an improperly presented crown, as indicated in Fig. 25, to prevent such crown from moving through the offset passage between the plates, and for preventing the crown from jamming in this position. During the rotation of the selector plates, such improperly presented crown will be lifted and will finally fall back into the hopper to be further agitated. As indicated in Fig. 26, a properly presented crown will not be stopped at the shoulder 163, since the rounded edges of the crown will merely ride over the conical surface 163' of the selector plate 144, and thus permit the crown to pass to the periphery of the plates. To facilitate the movement of properly presented crowns, the face of the selector plate 144 defining one wall of the crown passage is provided with a 75 80 85 90 95 100 105 110 115 120 125 130

shallow concave groove 164 concentric with the axis of the plate.

The lower portions of the annular rib 143 are provided with a notch 165, which registers with a crown chute 166 pivotally suspended by means of a pin 167 to the lower portion of the crown hopper. The crown chute includes a curved lower portion terminating in a lip 168 which is slidably engageable with the projecting parts 133 of the bottle centering guides 127. As seen in Figs. 17 and 19, a gate 169 is pivotally mounted at the lower end of the chute to form one side wall of the chute channel, and is normally urged to its closed position by a spring 170. When it is desired to remove a defective crown from the chute, it is only necessary to displace the swinging gate outwardly against the action of its spring, thus providing an opening through which the crown may be withdrawn. The crown chute is held in its proper position with respect to the capping heads by a removable pin 171 passing through a lug 172 formed on the crown chute and also through a bracket 173 fixedly depending from the extension 80 of the capping head support. Upon the removal of the pin 171, the crown chute may be swung outwardly from the capping heads about its pivot pin 167. The crown chute is provided with a crown rejector which includes deflectors 174 disposed at the opposite side walls of the crown chute and engageable with the flanges of an improperly presented crown to shunt the crown through an opening 175 in the chute and into a receptacle 176. In order to facilitate the movement of the crowns along the crown chute, the inner wall of the chute is made convex, as seen in Fig. 20, and the outer wall is formed by a medially located guide bar 177 extending lengthwise of the chute and mounted on cross bars 178, which are secured to the chute by screws 179. The guide bar 177 is engaged by the flaring edges of the crowns, as seen in Fig. 20. At the lower portion of the chute, guide lips 180 are secured to the chute to form additional support for the crowns. During the revolution of the capping heads, the discharge end of the crown chute intermittently registers with the crown receiving cavities of the capping heads, and at all other times the lower end of the crown chute is blocked by the curved outer surfaces 55 of the capping head sector bodies 118.

The bottles to be crowned are conducted to and away from the capping table 62 in any suitable manner. Where the capping mechanism forms part of a combined filling and closing machine, the bottles may be transferred from the filling mechanism 181 to the capping table by means including a star wheel 182, as indicated in Fig. 2. The bottles are conducted away from the capping table 60 between suitable guides 183, which lead the

bottles to a flat-topped conveyor chain 184. The incoming bottles may be conducted to the filling mechanism from the same conveyor chain 184 by means of guides 185, which lead the bottles to a star wheel 186. The directions of rotation of the filling mechanism, capping table, and the transfer star wheels are indicated by arrows in Fig. 2. The star wheels 182 and 186 are carried at the upper ends of vertical shafts 187 and 188, respectively, which are journalled in the upper portion of the bearing bracket 36, and which are driven at the proper speed in any suitable manner, as by means of gears 189 at their lower ends meshing with the ring gear 53. 80

The U-shaped rocker frame 57 which reciprocates the capping rod 61 may also be used to operate parts of the filling mechanism, such as the filling siphons, valves, or bottle lifters. For this purpose, a pair of vertical rods 190 are slidably mounted in the upper portions of the bearing bracket 36 to extend therethrough and bear at their lower ends on the upper surfaces of the arms 56 of the rocker frame. At their upper ends, the rods 190 are connected by a horizontal plate 191 which is engageable with the lower ends of rods 192 for operating filling siphons or valves. 90

The driving mechanism for the machine is located within the hollow base 35, where it is well protected against tampering and entrance of foreign matter, and where there is no danger of injury to the attendant. The gearing connections are such as to permit the use of a relatively simple structure for accomplishing the various functions of the machine. 100

In operation, the rotary capping table 62 carried on the sleeve 41 is rotated through gearing connections, heretofore described, including the gears 42, 51, 50, and 49, and simultaneously the rod 161 within the tubular standard 39 is reciprocated by the crank operated rocker frame 57. In the present instance, the rod is given five complete reciprocations for each revolution of the capping table, corresponding to the number of capping heads. The rotary spool 74, carrying the five capping heads, is driven synchronously with the capping table by its splined connection with the upper portions of the rotary sleeve 41. As soon as the upper segment 85 of one of the capping heads leaves the supporting ledges 86 and 87 on the capping head support, the segment is deposited onto the lower inwardly projecting end of the hook member 101, and at this point, the capping rod 61 moves downwardly carrying with it the capping head which simultaneously slides along the hook member 101. A bottle crown has been previously deposited through the crown chute onto the ledge members 135 of the capping head in readiness for the crowning operation, and upon the downward 115

movement of the capping head, the bottle neck is guided into the capping head and engages the crown, the crown being pushed onto the bottle neck by the spring-pressed 5 ejector plunger 114. As the capping rod approaches its lowermost position, the toggle member 109 is brought into engagement with the upper flat face of the segment 85 under the pressure of the spring 99, thus urging 10 the capping head downwardly and crimping the crown, which is now in the crowning die or throat 122, firmly about the bottle neck. During the further movement of the bottle segment 85, the toggle member swings about 15 its pivotal mounting in the plunger 106, thus creating a powerful crowning pressure while avoiding any appreciable sliding movement of the toggle member on the segment during the application of the crowning pressure. As 20 the capping rod 61 rises, the capping head also rises by the reaction of the spring 116 which acts through the ejector plunger 114 to push the crowned bottle out of the crowning throat. After the ejector plunger is released from the bottle, the capping head is 25 lifted by the hook member 101 until the segment 85 is in register with the ledges 86 and 87, whereupon the continued movement of the capping head brings the segment into 30 sliding engagement with these ledges. The bottle is then discharged from the capping table and, as the capping head revolves, it receives another crown from the crown chute 166. The cycle of operation is then repeated 35 with the next capping head.

In the modified form of capping machine shown in Figs. 27 to 30 inclusive, the numeral 210 designates a rectangular marginally flanged base plate which is supported from 40 the floor on vertically adjustable jack pedestals 211. A rectangular platform 212 provided with depending marginal flanges 213 is supported above the base plate 210 in fixed position by pillars 214. A terraced channel 45 215 is formed in the upper surface of the platform 212 near and parallel to one edge to receive and guide therein the upper flight of a bottle conveyor chain 216, the upper surface of which is substantially flush with the 50 upper surface of the platform. The conveyor chain 216 may extend beyond the opposite ends of the platform 212 any desired distance, and in the present instance, one end of the chain passes over a sprocket 217 which 55 is rotatably mounted in an outrigger bracket 218 secured to the platform at an end of the chain-receiving channel 215. The lower flight of the chain may be supported in a channel plate 215' suspended below the platform 212, as seen in Fig. 27. The upper flight of the bottle conveyor chain travels in the direction indicated by an arrow in Fig. 60 29. The sprocket 217 at the discharge end of the chain 216 is the propelling sprocket 65 for the chain, and is mounted on a shaft 220

carrying a driving sprocket 221 and journaled in the bracket 218 and in another bracket 222 spaced laterally from the bracket 218. The sprocket 221 meshes with a chain 297 which is driven in any suitable manner. 70

A hollow column 270 is fixedly secured to the upper face of the base plate 210 and supports therein in splined relation for longitudinal sliding movement a vertical shaft-like pillar 271, the pillar having a threaded lower end portion 272 on which is screwed a hand wheel 273 whereby the pillar may be adjusted in elevation. A rotary capping table 274 surrounds and is journaled on an intermediate portion of the pillar 271, and is carried in axial thrust relation on the upper end of the column 270 through an interposed anti-friction bearing 275. The rotary table 274 is provided with a surrounding gear 276 which meshes with a ring gear 227 forming part of a co-ordinated bottle filling mechanism, not shown. The ring gear meshes with a pinion 228 (seen in Fig. 27) secured to a shaft 229 journaled in a bearing bracket 230 mounted on the base plate 210. The vertical shaft 229 carries a bevel gear 231 meshing with a bevel pinion 232 keyed at one end of a horizontal shaft 233, which is also journaled in the bearing bracket 230. The other end of the horizontal shaft 233 carries a gear wheel 234 which meshes with a laterally adjacent pinion 235 secured to one end of a horizontal shaft 236 journaled in bearing brackets 237, the other end of the shaft 236 carrying a pulley 238 which is driven by any suitable source of power, such as an electric motor. 90

The upper face of the rotary capping table 274 carries a resilient bottle-receiving capping disk 274' which is substantially flush with the upper surface of the platform 213, there being a circular opening in the platform slightly larger than the table to permit the free rotation of the table. 105

A central sleeve 277 forming part of the table 274 projects upwardly above the disk 274' to surround the stationary pillar 271 on which it is journaled. The sleeve has a splined connection with the lower portion of a capping head turret 278 which also has a bearing on the upper end portion of the stationary pillar 271. A bottle-receiving star wheel 277' is keyed on the sleeve 277 in adjustable elevation above the table 274. 110

The capping head turret carries a concentric circular group of vertically movable spring-mounted capping heads or plungers 279 which are supplied with caps or crowns through a chute 280 connected to a hopper 281. In the present instance, the upper end of each capping or crowning head 279 is provided with an arcuate flat-topped segment 282, the segments for the several capping heads being arranged in a circular group 125 concentrically disposed about the axis of the 130

turret 278, as seen in Fig. 29. A lever 283 is disposed above the capping head turret with a portion immediately above the capping station, and carries a conical roller 284 which rolls on the flat horizontal upper surface of the segments 282. At its forward portion the lever 283 is guided for vertical movement in a guide fork 283', and at its rear end, the lever is pivotally secured to one arm of a bell crank 285 which is pivotally mounted on a standard 286 bolted to the platform 212. The end of the bell crank 285 pivotally carrying a lever 283 normally engages the upper end of an abutment 287 on the standard 286. A coiled spring 288 adjusted to a suitable compression urges the other end of the bell crank 285 upwardly, so as to normally maintain the bell crank in engagement with the abutment 287. The free end of the lever 283 has pivotally secured thereto a depending reach rod 289, the lower end of which passes through the platform 212 and is guided for substantially vertical movement by its pivotal connection with the free end of a laterally extending link 290 (seen in Fig. 30) having its other end pivotally secured to the platform 212. A connecting rod 291 has its lower end mounted on a crank pin 292 on the gear wheel 234 and has its upper end pivotally secured to the lower end of the reach rod 289 at its pivotal junction with the free end of the link 290. By means of the above connection, the rotation of the gear wheel 234 effects the vertical reciprocation of the reach rod 289, which in turn rocks the lever 283 carrying the roller 284. On the downward movement of the reach rod 289, the roller 284 depresses the subjacent capping head 40 segment 282 for effecting the capping operation.

The filled bottles are transferred onto the rotary capping table 274 in any suitable manner, as by means including a star wheel 293 secured to the upper end of a suitably driven vertical shaft 294. The bottles are guided in their discharge from the capping table to the conveyor chain 216 by spaced guide plates 296 forming a bottle-receiving channel between them, as seen in Fig. 29, the guide plates 296 being preferably extended along the sides of the chain.

In the operation of the machine of Figs. 27 to 30 inclusive, the bottles are successively deposited on the rotary capping table where the bottles enter the notches of the star wheel 277', to properly locate them with respect to the superposed capping heads. As each capping head passes under the conical roller 284 of the lever 283, the lever is pulled downwardly by its crank connection with the rotating gear wheel 234, and the roller 284 thereupon engages the arcuate segment 282 to depress the attached capping head for effecting the capping of the subjacent bottle.

The capping operation takes place while the bottle is moving with the slowly rotating table 274, and during this interval, the conical roller 284 rolls over the arcuate segment 282 on the capping head as the crank operated lever 283 is first depressed and then elevated, the capping head being in its lowest position when the roller is at the central portion of the segment. After the capping operation, the capping head is elevated by its spring, and during the next depression of the lever 283, the roller acts on the succeeding arcuate segment which comes into position beneath the roller. The capped bottles are then guided off the capping table and onto the conveyor chain 216 by the guide plates 296, whereupon the bottles are conducted to the discharge end of the chain. The capping heads in their further revolution receive crowns from the crown chute 280.

During the capping operation, capping pressure is determined by the compressed coiled spring 288 acting on the lever 283 through the bell crank 285, and if the capping head meets with unusual resistance, the inner end of the lever 283 will rise above the abutment 287, thereby avoiding excessive crowning pressure. The spring 288 is compressed to an extent several times greater than the maximum spring action to obtain the initial crowning pressure, so that this pressure will increase only a small amount during the capping of a bottle which is longer than normal. With this capping arrangement, the capping pressure varies negligibly with longer or shorter bottles. The term "capping" as herein used is not confined to the application of any particular type of container closure.

What I claim as new and desire to secure by Letters Patent is:

1. In a container closing machine, the combination of a container support, a revoluble group of capping heads disposed above said support, a plurality of segments respectively carried on said capping heads, and reciprocatory actuating means for successively depressing said capping heads as they revolve into capping position, said reciprocatory means including a pivotally supported member engageable with the upper faces of said segments.

2. In a container closing machine, the combination of a container support, a revoluble group of capping heads disposed above said support, a plurality of segments respectively carried on said capping heads, and reciprocatory actuating means for successively depressing said capping heads as they revolve into capping position, said reciprocatory means including a toggle member engageable with the upper faces of said segments.

3. In a container closing machine, the combination of a container support, a revoluble group of capping heads disposed above said

- support, a lever engageable with said capping heads for successively depressing said capping heads as they revolve into capping position, means for reciprocating said lever, 5 and a yieldable fulcrum for said lever.
4. In a container closing machine, the combination of a container support, a capping head disposed above said support, a lever for actuating said capping head, a second spring-loaded lever pivotally secured to said first-named lever for providing a yieldable fulcrum for said first-named lever, and means for periodically operating said first-named lever to depress said capping head.
- 10 5. In a container closing machine, the combination of a lower container support, a stationary upper capping head support disposed above said container support, a revoluble group of capping heads suspended from said upper support, and reciprocatory means common to said capping heads for successively depressing said capping heads as they revolve into capping position and for elevating said capping heads into supported engagement with said upper support.
- 15 6. In a container closing machine, the combination of a hollow support, a rotary container-supporting table surrounding said support, a rotary turret disposed above said table, a plurality of vertically movable capping heads carried on said turret, a reciprocatory rod extending within said hollow support, operating means for said rod, and means carried on the upper portion of said rod for successively depressing said capping heads as they revolve into closing position.
- 20 7. In a container closing machine, the combination of a container support, a stationary capping head support disposed above said container support, a revoluble group of capping heads suspended from said upper support and having segments at their upper portions slidably resting on said upper support, and reciprocatory actuating means common to said capping heads and including portions engageable with said segments for successively depressing said heads from said upper support as they revolve into capping position, said actuating means including other portions engageable with said capping heads for elevating said heads into supported engagement with said upper support.
- 25 8. In a container closing machine, the combination of a container support, a capping head disposed above said support, a reciprocatory rod having an operative connection with said capping head, a pivotally supported rocker frame having laterally spaced arms, means for pivotally connecting said rod to said rocker frame intermediate said spaced arms, and a rotary member having crank connections with each of said arms for reciprocating said rocker frame and connected rod.
- 30 9. In a container closing machine, the combination of a container support, a capping head disposed above said support, a reciprocatory rod having an operative connection with said capping head, a pivotally supported forked rocker frame having spaced arms, means for pivotally connecting said rod to said rocker frame intermediate the spaced arms of the rocker frame, and a rotary member disposed between the spaced arms of said rocker frame and having crank connections with said arms for reciprocating said rocker frame and connected rod.
- 35 10. In a container closing machine, the combination of a tubular standard, a container support disposed about said standard, a capping head disposed above said standard, a reciprocatory rod disposed within said support and operatively connected with said capping head, a pivotally supported rocker frame adjacent the lower end of said standard, a trunnion journaled in said rocker frame and having a threaded connection with said rod, a rotary member having a crank connection with said rocker frame for reciprocating said rocker frame and connected rod, and means for rotating said rod for adjusting the elevation of said capping head with respect to the container support.
- 40 11. In a container closing machine, the combination of a container support, a reciprocatory capping head disposed above said support, a supporting member for said capping head, a hollow standard, a sleeve having a threaded connection with said standard and sustaining said head-supporting member, a reciprocatory rod disposed within said sleeve and standard and having an operative connection with said capping head, said rod and sleeve being secured against relative rotation, a reciprocatory actuating member having a threaded connection with said rod, and means for simultaneously rotating said sleeve and rod to adjust the elevation of said capping head and its supporting member for accommodating containers of different height.
- 45 12. In a container closing machine, the combination of a container support, a reciprocatory capping head disposed above said support, a supporting member for said capping head, a hollow standard, a sleeve having a threaded connection with said standard and sustaining said head-supporting member, a reciprocatory rod disposed within said sleeve and standard and having an operative connection with said capping head, said rod and sleeve being secured against relative rotation, a reciprocatory actuating member having a threaded connection with said rod, a gear carried on said sleeve, and gearing means meshing with said gear for simultaneously rotating said sleeve and rod to adjust the elevation of said capping head and its supporting member for accommodating containers of different height.
- 50 13. In a container closing machine, the combination of a container support, a capping

combination of a hollow base including an upper wall, a tubular standard upstanding from said upper wall, a rotary sleeve surrounding said standard and including a portion below said wall, a rotary container support carried on said sleeve above said upper wall, gearing connections disposed below said wall for rotating said container support, a capping head support carried at the upper portions of said standard, a capping head carried on said last-named support, a reciprocatory rod disposed within said standard and having an operative connection with said capping head, the lower end of said rod being below the upper wall of said base, and means disposed below said wall for reciprocating said rod.

14. In a container closing machine, the combination of a rotary container support, a capping head disposed above said support, a capping head support, and means extending substantially axially of said container support for reciprocating said capping head and adjusting the elevation of said capping head support to accommodate bottles of different height.

15. In a container closing machine, the combination of a container-supporting means, a revolute group of capping heads above said supporting means, and reciprocatory actuating means for successively operating said capping heads as they revolve into capping position and including a pivotally mounted member engageable with said capping heads.

16. In a container closing machine, the combination of container-supporting means, a revolute group of capping heads above said supporting means, a reciprocatory member arranged substantially along the axis of said capping head group, operating means for said member, and means carried on said member for successively operating said capping heads.

17. In a container-closing machine, the combination of container supporting means, a revolute group of capping heads above said supporting means, reciprocatory actuating means for successively operating said capping heads as they revolve into capping position, and spring means for said actuating means placed under a substantial deflection-produced initial stress to minimize the variation in capping pressure applied to containers which are shorter or longer than normal.

In testimony whereof I affix my signature.

GEORGE J. MEYER.
